UNITED STATES PATENT OFFICE.

WILLIS E. SNIDER, OF CHICAGO, ILLINOIS, ASSIGNOR TO MUTUAL METAL MANUFACTURING COMPANY, OF CHICAGO, ILLINOIS.

DESIGN FOR A LIGHTING FIXTURE.

Application filed November 6, 1922. Serial No. 4,229. Term of patent 3½ years.

To all whom it may concern:

Be it known that I, WILLIS E. SNIDER, a citizen of the United States, and a resident of the city of Chicago, in the county of Cook, in the State of Illinois, have invented a new, original, and ornamental Design for a Lighting Fixture, of which the following is a specification, reference being had to the accompanying drawings, in which—

Figure 1 is a side elevation of the lighting fixture.

Figure 2 is a bottom plan thereof.

I claim:

The ornamental design for a lighting fixture as shown.

WILLIS E. SNIDER.
